(57) **CLAIM**

We claim the ornamental design for a LED replacement module, as shown and described.

DESCRIPTION

FIG. 1 is a front perspective view of a LED replacement module in accordance with the present design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines are for illustrative purposes only and form no part of the claimed design. Any shading forms no part of the claimed design and is provided to illustrate contour only and is not an indication of texture, gloss, and the like.
